(57) CLAIM

The ornamental design for a toilet lid and seat, as shown and described.

DESCRIPTION

FIG. 1 is a perspective view of a first embodiment of a toilet lid and seat design in a partially open position;

FIG. 2 is a front view of the toilet lid and seat design of FIG. 1;

FIG. 3 is a first side view of the toilet lid and seat design of FIG. 1;

FIG. 4 is a second side view of the toilet lid and seat design of FIG. 1;

FIG. 5 is a top view of the toilet lid and seat design of FIG. 1; and,

FIG. 6 is a second perspective view of the toilet lid and seat design of FIG. 1 in a closed position.

The broken line disclosure represents unclaimed portions of the toilet lid and seat in which the design is embodied.

1 Claim, 6 Drawing Sheets
